UNITED STATES PATENT OFFICE.

HENRY M. RYDER, OF TAUNTON, MASSACHUSETTS, ASSIGNOR OF ONE-HALF
TO LLOYD E. WHITE, OF SAME PLACE.

WRENCH.

SPECIFICATION forming part of Letters Patent No. 380,353, dated April 3, 1883.

Application filed October 10, 1887. Serial No. 251,957. (No model.)

To all whom it may concern:

Be it known that I, HENRY M. RYDER, of 5
Taunton, in the county of Bristol and Com-
monwealth of Massachusetts, have invented a
new and useful Combined Hub and Wrench,
of which the following is a specification, ref-
erence being had to the accompanying draw-
ings, which form a part hereof.

The object of my invention is a hub and 10
wrench which can be so combined that the
wheel may be readily removed from the axle
without detaching the nut from its seat in the
hub.

My invention consists in a hub having an 15
annular slotted flange upon the inside near its
outer end, in combination with a wrench com-
posed of a head having a diminished socket por-
tion adapted to pass inside the annular flange
and fit on the nut, and spring-jaws with levers
20 pivoted in the side of the head, the jaws being
formed with a neck to fit in the slot of the an-
nular flange, and a cross-piece on the end hav-
ing a shoulder or clutch, so that when the
wrench is fitted over the nut and the wheel is
25 rotated to bring the neck of the jaw against
the slot in the flange it will lock itself, and the
backward rotation of the wheel will unscrew
the nut without loosening it from its seat.

In the drawings, Figure 1 is a longitudinal 30
vertical section through the wrench, hub, and
axle, with the wrench fitted on the nut, and the
jaws clutched under the flange before being
locked. Fig. 2 is a similar section when the
wheel has been partially revolved to bring
35 the necks of the jaws in the slots of the flange.
Fig. 3 is an end view of the hub and axle, show-
ing the slotted flange on the inside of the hub.
Fig. 4 is an outer end view of the wrench, and
Fig. 5 an inner end view. Fig. 6 is a longi-
40 tudinal section of the wrench with the jaws
closed, and Fig. 7 is a similar section when
the jaws are open. Fig. 8 is a side view of the
head of the wrench with the jaws removed.
Fig. 9 is an outside view of one of the jaws and
45 levers.

The hub-band A is formed with an inside
annular flange, *a*, having in the edge notches
or slots *a'*.

The wrench consists of a head having a
50 socket-piece, B, of diameter small enough to
pass inside the annular flange *a* of the band,

and having a socket to fit the nut E. The
outer end of the head has a rim, *b*, of greater
outside diameter than the inside diameter of
the flange *a*, to prevent the head from passing 55
entirely through. In the edge of this rim *b*
are pivoted the levers D of the jaws. A spring,
d, holds the jaws open when not compressed.
Each jaw is formed with a neck, *d'*, and a cross-
piece having a shoulder, *d''*, to clutch the un-
der side of the flange *a*, and tapering toward
the end for convenience in passing it through
the flange. The socket-piece B is preferably
60 made slightly tapering, and with recesses *b'* in
extension of the slots *b'*, within which the le-
vers are pivoted to receive the jaws, so that
when closed they may be brought flush with
the surface, except the shoulder *d''*, which may
65 project slightly. The arms of the levers are
formed with bows *d*, for convenience in hand-
70 ling. The end of the cylinder or axle-box *g*
forms a seat for the nut E, the flange *e* serving
as a guard.

In operation, when it is desired to remove
the wheel, the wrench is taken by the bows *d* 75
like a pair of scissors, and the levers are spread
apart, thus closing the jaws into the recesses
b', and enabling it to pass inside the flange and
fit over the nut. It is only necessary to have
the socket square with the nut without regard 80
to the relative position of the slots *a'*. The fin-
gers are removed from the levers, and the
springs *d* partially open the jaws, as shown
in Fig. 1, so that the shoulder *d''* bears up
against the flange *a*, to prevent the wrench 85
from slipping out, but does not cause it to turn
with the wheel. The wheel is now partially
rotated in either direction to bring the necks
d' against the slots *a'*, when the springs *d* open
the jaws still farther, throwing the necks *d'* 90
into the slots, thus locking the wrench and
preventing further rotation of the wheel with-
out the wrench and nut turning at the same time
with it, while, the cross-piece being longer than
the slot, the jaw will not slip out endwise. The 95
wheel is now rotated backward, carrying
around with it the wrench and nut all locked
together, and the nut is unscrewed, leaving the
wheel free to be removed, the wrench and nut
still being locked in the hub. When the wheel 100
is to be replaced upon the axle, the hub is
pushed on until the end of the spindle enters the

nut, when the wheel is rotated in the reverse direction from that by which it was unscrewed, the nut and wrench being again rotated with the wheel until the nut is screwed on. The jaws 5 of the wrench are then closed by spreading the levers and the wrench is easily removed.

What I claim as my invention is—

The combination of a hub having an annular slotted flange upon the inside, and a wrench 10 composed of a head formed with a diminished socket portion to pass inside the flange and fit over the nut, and spring-jaws with levers pivoted in the side of the head, the jaws being

formed with a neck to fit in the slots of the flange, and a cross-piece on the end having a 15 shoulder or clutch, so that when the wrench is fitted on the nut and the wheel is partially rotated to bring the necks of the jaws against the slots in the flange the springs will throw the necks into the slots and lock the wrench, nut, 20 and hub together, substantially as described.

HENRY M. RYDER.
